UNITED STATES PATENT OFFICE.

JOSEPH HIGGINSON, OF STOCKPORT, ENGLAND.

METHOD OF MAKING SPINNING RINGS.

Application filed June 4, 1924. Serial No. 717,880.

This invention has for its object to provide simple and efficient means for ensuring that the rings of ring spinning, doubling and like machines shall be truly or 5 practically concentric when in position in the ring rail.

My invention comprises the improved method of producing rings and placing the same in the ring rail according to which 10 the ring is first forced upon a taper mandrel so that the bore of the ring is made truly circular, the ring being then ground whilst still upon the mandrel so that its 15 external periphery which fits into the ring rail is made truly circular, and then fitted into the ring rail whilst still upon a mandrel, the latter being then withdrawn, after 20 which the ring rail itself resists any tendency of the ring to become excentric or to distort.

Referring to the accompanying sheet of explanatory drawings:—

Figure 1 is a plan of part of a ring rail having a ring secured therein.

25 Figure 2 is a sectional end view through the ring and rail.

Figure 3 is an elevation of the ring, the rail being shown in section.

The same reference letters in the three 30 views indicate the same parts.

In one convenient application of our invention, the ring *a* is made of any usual cross section or it may be made with a tapered or conical part *b* on its exterior 35 which is adapted to fit in a correspondingly tapered aperture in the ring rail *c*. After the ring has been machined in the ordinary way, it is forced upon a tapered mandrel, such as is illustrated by dotted lines at *e* in 40 Figure 3, which makes the bore of the ring truly circular. The ring is now ground whilst still upon the mandrel so that the exterior of the ring is made truly concentric with the bore of the ring. The latter 45 may now be removed from the mandrel, when it will again show the internal distortion which the mandrel corrected. If desired, the point where the ring bulges outwards the most may now be marked and a 50 groove *f* be formed on the outside of the ring at the said point.

The apertures for the rings in the ring rail are made of very great circular ac-

curacy. Each ring is again placed upon a mandrel to make its bore truly concentric 65 when the external periphery also becomes concentric due to the previous grinding process before described. The rings are then forced into the rails and thereafter the mandrels are withdrawn downwards. 70 The ring rail now resists any tendency of the ring to become excentric or to distort. The set screw *d* is screwed against the grooved part of the ring periphery and removes any inaccuracy in the ring due to the 75 natural tendency to bulge at the part in question. The said set screw also holds the ring in place.

By the employment of my invention, I 80 find that I can provide rings having practically uniform circular bores which ensures a more efficient and uniform action of the traveller (not shown).

I claim:—

1. A method of producing rings for ring 75 spinning, doubling and like machines consisting in first machining the rings in the usual manner, then forcing the machined ring upon a tapered circular mandrel so that the bore of the ring is made truly 80 circular, grinding the periphery of the ring while the latter is on the mandrel to make the periphery truly concentric with the bore of the ring, and afterwards forcing the ring 85 whilst upon a mandrel into the aperture of a ring rail, whereby when the last mentioned mandrel is withdrawn from the ring, the latter is held against distortion by the rail.

2. A method as claimed in claim 1 in 90 which the bore of the aperture in the ring rail is coned and in which the periphery of the ring is ground to substantially conical form so that it will snugly fit into said aperture. 95

3. A method as claimed in claim 1 having the added steps of forming a groove in the periphery of the ring at the point where the ring tends naturally to bulge or distort the most when the mandrel is withdrawn 100 therefrom, and placing a screw in the ring rail to engage said groove.

In testimony whereof I have signed my name to this specification.

JOSEPH HIGGINSON.
